[57] CLAIM

The ornamental design for a seat, as shown and described.

DESCRIPTION

FIG. 1 is a perspective view of a seat showing my new design;

FIG. 2 is a front elevational view thereof;

FIG. 3 is a top plan view thereof; and,

FIG. 4 is a left side view thereof, the opposite side being a mirror image of the side shown.

The rear is plain and conforms to the design shown in FIGS. 1 through 4.
